UNITED STATES PATENT OFFICE

2,440,169

STOCKING DRYER

Malvina Diamant, New York, N. Y.

Application November 7, 1946, Serial No. 708,301

1 Claim. (Cl. 34—95)

1

This invention relates to drying means and more particularly to a device adapted to hasten the drying of stockings and other lingerie.

As is well known, it is customary for ladies to rinse out stockings and other lingerie and they have in the past experienced considerable difficulty in drying such items where it is not possible or practical to place them on the line.

The object of this invention is to provide a medium for drying hosiery and similar items which may be hung in an apartment, kitchen or bathroom or any suitable place and which will hasten the drying of the items. A further object is to provide a device which, when not in use, may be easily stored in a bureau drawer, closet shelf or elsewhere. Other objects and advantages will become apparent from the accompanying description in which:

Figure 1 is a plan view partly in perspective of the dryer embodying my invention.

Figure 2 is a cross sectional view thereof.

Figure 3 shows the dryer in a rolled position.

Figure 4 shows a slight modification.

Figure 5 is a perspective view of the form shown in Figure 4.

Referring more particularly to the drawings, dryer 10 may consist of a single element or a double element as shown. A head member 11 is furnished with a suitable hanger 12 pivoted thereto. Depending from the head member 11 is a flexible member 15, preferably made of turkish toweling or other highly absorbent material. As previously stated, one or more drying elements 15 may be hung from the head piece 11.

Adjacent to the top of the drying element 15 is a band or holding element 16 stitched at 17 to the drying element or otherwise fastened. Preferably a rod 18 in the lower end 19 of the drying element 15 and hooks 20 are provided in the head piece to engage the rod when the drying element is rolled up.

In use, a damp stocking 25 is draped over the holding member 16 as shown in Figure 1 and several stockings can be so hung. The drying element is then rolled upon itself to squeeze the remaining moisture out of the stocking and the rod 18 secured in the hook 20. In the modification shown in Figure 4, the hooks 20 are eliminated and a tape 30 having a snap fastener or button 31 is provided to hold the rolled drying element in the closed position.

While in my description I have described the drying element as preferably of an absorbent material such as turkish toweling, any other suitable material may be used. By the same token, other means for fastening the rolled up drying element may be equally well used.

It will be appreciated that what I have shown and described is but a preferable form of my invention and that many modifications can easily be made without departing from the respective idea.

I claim:

A device of the character described, comprising a head piece, a pair of absorbent sheet members depending from said head piece, a strip of material sewn to each of said sheet members for holding stockings or the like, a rod in the lower portion of said sheet members and means on said head piece to engage said rod when said sheet members are rolled to hold them in a rolled position.

MALVINA DIAMANT.
